(57) **CLAIM**

The ornamental design for a swivel release for fishing lure, as shown and described.

DESCRIPTION

FIG. 1 is an exploded perspective view of a swivel release for fishing lure, showing my new design;

FIG. 2 is an exploded front view thereof;

FIG. 3 is an exploded rear view thereof;

FIG. 4 is an exploded right side view thereof;

FIG. 5 is an exploded left side view thereof;

FIG. 6 is an exploded top view thereof;

FIG. 7 is an exploded bottom view thereof;

FIG. 8 is perspective view thereof; and,

FIG. 9 is an environmental view thereof.

The broken line showing of a fishing lure and fishing line is for the purpose of illustrating environment and forms no part of the claimed design.
